Nelson N. Howard

UNITED STATES PATENT OFFICE.

JAMES WILLIAM MELOON, OF WELLESLEY, MASSACHUSETTS, ASSIGNOR TO UNITED SHOE MACHINERY CORPORATION, OF PATERSON, NEW JERSEY, A CORPORATION OF NEW JERSEY.

ATTACHMENT OF SOLES TO SHOES.

Application filed October 4, 1926. Serial No. 139,429.

This invention relates to improvements in shoes and to the manufacture and repairing thereof and is illustrated herein with reference to the repairing of a turn shoe. 5 The repairing of turn shoes, at least without removing their outsoles, stitching the uppers wrong-side out to new outsoles, and turning and refinishing the shoes, has long been unsatisfactory and impractical. Moreover, 10 the ordinary shoe repair shop is not equipped to do such work. Even if it were the condition of many of the turn shoes brought in by customers for repairing is such that the cost would be out of proportion to the value of the shoes when repaired. It is, 15 accordingly, an object of the present invention to provide a simple and satisfactory method applicable to the repairing of turn shoes and sufficiently cheap to make its use 20 economically sound even when the shoes, aside from the worn sole, are not in such condition as to warrant lasting of the shoe upper wrong-side out relatively to a new sole and turning and subsequently refinishing the shoe. In another aspect this invention relates to the manufacture of shoes, for the method herein disclosed is not limited 25 in its utility to repair work.

As illustrated herein, the novel method is characterized by the attachment of a sole member to a shoe by staples arranged with their bars substantially at right angles to the edge of the sole. With the staples so located, their tendency to interfere with the flexibility of the shoe is practically eliminated, a shoe with its sole attached in this manner being much more flexible than a similar shoe having its sole attached by staples having their bars parallel to the edge of the shoe. 35

In another aspect the invention comprises a shoe having a sole member attached by staples arranged with their bars substantially at right angles to the edge of the sole member.

With the above and other objects and features in view the invention will now be described with reference to the accompanying drawings and pointed out in the claims.

In the drawing,

Fig. 1 is a perspective view of a shoe, positioned sole upwardly and having a half-sole attached by means of staples located in a

channel with the bars of the staples at right angles to the edge of the sole;

Fig. 2 is a sectional view, on a larger 55 scale, taken on the plane II—II of Fig. 1; and

Fig. 3 is a fragmentary, transverse, sectional view through the sole and part of the upper of the shoe prior to the attachment 60 of an outsole member thereto.

The invention is disclosed herein with reference to a turn shoe having an upper 10 attached to a sole member 12 by stitching 14 entering the edge 16 of the upper and 65 passing into the shoulder 18, through the between-substance 20, and into the channel 22 of the sole, as shown in Fig. 3. By the time such a shoe reaches the repair man its sole 12 will have been worn thin in the middle, as indicated at 24 (Fig. 3) and will be rounded off or somewhat worn at the edge, as indicated at 26. In repairing this shoe in accordance with my novel method, the sole is trimmed to a feather edge, as indicated 70 at 28, the portion of the sole cross-hatched in Fig. 3 being removed, for example by skiving it off. An outsole 30, preferably 75 channeled as indicated at 32 (Figs. 1 and 2), is then applied to the sole 12, which 80 thus becomes an inner sole member, and is attached thereto by staples 34 located in the channel and extending from the shank portion around the ball portion and the toe of the shoe and positioned with their bars 85 36 substantially at right angles to the edge of the outer sole member 30. While this outer sole member 30 is shown in Fig. 1 as a half-sole, it should be understood that this is for purposes of illustration only and that it may be longer, or possibly shorter, if desired.

The staples used for attaching soles in this fashion should be of moderately fine wire, for example wire about .025 by .045 of an inch. With the bars of staples formed from such wire positioned substantially at right angles to the edge of the sole and thus substantially parallel to the axis about which the sole flexes when the shoe is worn, women's shoes are not rendered objectionably 95 stiff as they are when they have their soles attached by other kinds of metallic fastenings.

While the invention has been disclosed

herein with reference to the repairing of turn shoes, it should be understood that it is not limited thereto since it is in some of its aspects applicable also to the manufacture and repairing of other types of shoes.

Having described the invention, what I claim as new and desire to secure by Letters Patent of the United States is:

1. That improvement in methods of repairing shoes which comprises trimming to a feather edge the edge portion of the sole of a shoe which is to be repaired and attaching a sole member to the sole so trimmed by staples extending from the shank around the ball portion to the toe of the shoe and positioned with the bars of the staples substantially at right angles to the edge of the sole member.
2. That improvement in methods of repairing turn shoes which comprises skiving to a feather edge the edge portions of the sole of a turn shoe which is to be repaired, applying a channeled sole member to the sole so skived, attaching the channeled sole member to the skived sole of the shoe by staples driven through the channel of the sole member into the skived sole with the bars of the staples arranged substantially at right angles to the edge of the sole, and closing the channel flap to conceal the bars of the staples.
3. That improvement in methods of repairing turn shoes which comprises skiving to a feather edge the edge portions of the sole of a turn shoe which is to be repaired, applying a channeled sole member to the sole so skived, attaching the channeled sole member to the skived sole of the shoe by a row of staples extending along both side edges and around the forepart of the channeled sole member, said staples being driven through the channel of the sole member into the skived sole with the bars of the staples arranged substantially at right angles to the edge of the sole, and closing the channel flap to conceal the bars of the staples.
4. A method of attaching soles to shoes

characterized by driving a row of staples through an outer sole member into an inner sole member attached to a shoe from the shank around the ball portion and toe of the shoe with the bars of the staples substantially at right angles to the edge of said sole members.

5. A method of repairing shoes which comprises applying to a shoe an outer sole member channeled about its periphery, driving staples through the channel of said sole member into an inner sole member and the shoe upper with the bars of the staples substantially at right angles to the periphery of said sole members, clenching the ends of the legs of the staples inside the shoe, and closing the channel flap to conceal the staples.

6. A shoe having an outer sole member attached thereto by a row of staples extending substantially parallel with a side edge of the sole member with the bars of the staples arranged substantially at right angles to the edge of the sole member.

7. A shoe having an outer sole member attached thereto by a row of staples extending around the ball and forepart of the shoe with the bars of the staples arranged substantially at right angles to the edge of the sole of the shoe.

8. A shoe having an inner sole member and an outer sole member attached thereto by staples positioned with their bars substantially parallel to the axis about which the sole of the shoe flexes when the shoe is worn.

9. A shoe having an inner sole member and an outer sole member attached thereto by a row of staples extending along the edges of the ball portion of the sole members, said staples being driven in a channel of the outer sole member with their bars positioned substantially at right angles to the edge of the sole and being concealed by a channel flap of the outer sole member.

In testimony whereof I have signed my name to this specification.

JAMES WILLIAM MELOON.
